UNITED STATES PATENT OFFICE.

WILLIAM WRIGHT, OF CHICAGO, ILLINOIS, ASSIGNOR, BY MESNE ASSIGNMENTS, TO CHICAGO-CLEVELAND CAR ROOFING COMPANY, OF CHICAGO, ILLINOIS, A CORPORATION OF DELAWARE.

UNCOUPLING DEVICE.

Application filed October 30, 1924. Serial No. 746,814.

To all whom it may concern:

Be it known that I, WILLIAM WRIGHT, a citizen of the United States of America, and a resident of Chicago, in the county of Cook 5 and State of Illinois, have invented a new and useful Improvement in Uncoupling Devices, of which the following is a specification.

This invention relates to uncoupling devices for railway cars, and more especially to heavy duty uncouplers involving the use of multiplying compound leverage means. The main objects of the invention are to provide an improved and more efficient form 15 of uncoupler of the character described; to provide a compound leverage uncoupling mechanism of compact character comprising few parts and assembled in a manner adapted for protection from injury and also convenient of access for repairs and interchange of 20 parts.

Several embodiments of this invention are shown by the accompanying drawings, in which—

25 Fig. 1 is mainly a plan of one embodiment of the invention attached to a railway car, the latter being in horizontal section just above the uncoupler.

Fig. 2 is a front elevation of the device 30 mounted in place on the car.

Fig. 3 is a greatly enlarged front view of the multiplier leverage mechanism in its normal position, including the housing or rocker box, which here serves also as a leverage element, the pivot bracket which is hidden being indicated by dotted lines and the box cover being removed as indicated by the section line 3—3 on Fig. 5.

Fig. 4 is a vertical axial section on the line 40 4—4 of Fig. 3.

Fig. 5 shows the bracket and leverage mechanism in plan, except that the box which serves in part as a lever is shown in horizontal section through the pivotal axis.

45 Fig. 6 is a front elevation of the device as in Fig. 3, but with the box and the rest of the leverage mechanism tilted counter-clockwise to the uncoupling position.

Fig. 7 shows a somewhat simplified embodiment, the view being mainly a plan of the bracket and levers with the box in horizontal axial section, substantially as in Fig. 5.

Fig. 8 is a front elevation of the device of

Fig. 7 with the cover removed as indicated 55 by the section line 8—8 in Fig. 7.

Fig. 9 representing a third embodiment is substantially similar to Fig. 7, except that a round disk-like and more symmetrical looking box is represented and a shoulder 60 is provided in the box instead of a pivot to impart power to the pin lifting lever.

Fig. 10 is also similar to Fig. 8 except for the disk shape of the box and the shoulder 65 construction referred to in Fig. 7.

Fig. 11 shows a fourth embodiment in which the box is omitted and a modified bracket and leverage combination is used.

Fig. 12 is a plan of the device of Fig. 11.

In the construction shown in Figs. 1 to 6, 70 the uncoupling device 1 is mounted on the end of a railway car 2 and is operatively connected to raise the knuckle lock pin 3 of the automatic coupler 4, as usual in railway practice. The uncoupler is of the power 75 multiplying compound leverage type adapted for use on cars equipped with heavy couplers, where the force required to operate same is greater than can be supplied readily through simple leverage devices. 80 The uncoupler embodiment 1 illustrated by said Figs. 1 to 6 comprises mainly a pivot fulcrum bracket 5, which is affixed to a seat member 2' bolted to the end of the car at the left of the coupler 4 and brake staff 6, 85 a leverage housing box 7 oscillatably mounted on said bracket, adapted to serve as a housing, a pair of main levers 8 and 9 arranged to function as hand operating and pin lifting levers respectively, and a short lever 10 operatively connecting the short end of said lever 9 and said box 7, said operating lever 8 being carried by the box 7 and said pin lifting lever 9 being mounted primarily on the fixed pivot 11 formed on 95 the upper right corner of bracket 5.

The power multiplying leverage mechanism or "chain" will now be more fully described. The hand lever 8 is fulcrumed at 12 on bracket 5 and its load is applied 100 medially at shoulder 13 on the lower left corner of box 7. Hence this is a lever of the second kind.

The leverage box 7 is fulcrumed on the main pivot 12. It receives its power at the 105 left shoulder 13 and carries its load at the right shoulder 14 (see Fig. 3). This is a lever of the first kind.

The lever 10 is fulcrumed medially on said pivot 12, receives its power at one end which bears against the shoulder 14 on box 7 and carries its load at the opposite end, 5 where it is pivotally connected as at 15 to the pin lifting lever 9. It is a lever of the first kind.

The pin lifting lever 9 receives its power at one end through pivot 15, is fulcrumed 10 medially on the stationary pivot 11 and carries its load 3 at the opposite end and is therefore a lever of the first kind.

In order to accommodate variation of the 15 effective length of the short primary arm of lever 9, it is provided with a longitudinal slot 16 to receive the sliding pivot or shoulder 15 on the link 10.

The operative relation of the hand lever 8 and the leverage box 7 is such that the 20 latter tilts coturnably with said lever. In order to accommodate the relative movement of said box and the fixed pivot 11, the back of said box is slotted as shown at 17. The relation of said pivot 11 and slot 17 is 25 shown by Figs. 3, 5 and 6. Said slot is ar- cuate and is arranged concentric with pivot 12. The pivot 11 is at the right of and somewhat higher than pivot 12, the direc- 30 tion being about 20° from horizontal.

In order to facilitate assemblage and 35 interchange or replacement of parts, the box 7 is formed in a rather flattish shape, set vertically and provided with a detachable face plate or cover 18 which is fastened in place detachably by means of a removable cotter pin 25 fitting in the perforation 20 in the outer tip of pivot 12. The outer edge of said cover is grooved and shouldered as at 18' to interfit with the corresponding 40 edges of the box so as to prevent relative edgewise movement of the box and cover. The right end wall of said box is widely 45 apertured at 21 to accommodate free relative movement of lever 9 both vertically and horizontally and also to permit sidewise as- 50 semblage of said lever not only when the box is mounted on bracket 5 with the pivots 11 and 12 projecting into the box, but also when the box is separated from said bracket.

The left end wall of the box is provided 55 with a vertical slot 22 for admitting the inner end of the hand lever 8. The cover 18 has an inwardly projecting boss 23 to serve as a stop for the lever 8 whereby the latter is secured in engagement with pivot 12 at the notch 24 on lever 8. When the cover 60 is in place, said stop locks the lever 8 in place against endwise withdrawal.

In assembling the device above described, 65 the bracket 5 is first secured to the end of the car by means of bolts or the like as shown at 5'. The pin lifting lever 9 is then inserted into the box 7 through the aperture 21. The box with the lever 9 in place

is then placed on the bracket pivot 12, care being taken that the bracket pivot 11 enters the box through slot 17 and also enters the corresponding aperture 9' of lever 9 at the point where the latter is fulcrumed. The 70 hand lever 8 is then thrust endwise into said box through the aperture 22 and the end having notch 24 is fitted against the box hub part 7' into which the pivot 12 fits coaxially. The lever 10 is then slipped 75 into place with its fulcrum part bearing against hub 7' and its right end seated against shoulder 14, care being taken that the pivot 15 on its left end enters the slot 16 of lever 9. The centrally apertured 80 cover 18 is then applied over the projecting tip of pivot 12 and the edges are fitted against the box at 18'. In so applying the cover the stud or boss 23 takes a position beneath and adjacent to the underside of 85 lever 8, whereby it serves to lock said lever in place in the box 7 and prevent downward movement of its inner end away from engagement with the hub 7'. The cover is then fastened in place by inserting the cot- 90 ter 25 as shown in Fig. 4.

When operated by downward pressure of the hand on lever 8, power is delivered 95 downwardly on the left side of box 7 which, by counter-clockwise leverage action, de- 100 liveres power upwardly against the right end of lever 10. Power is transmitted by said lever 10 to the left end of lever 9 where it is applied downwardly. This serves to tilt the pin end of lever 9 upwardly to raise 105 the knuckle lock pin 3. By this action the mechanism changes from the position shown by Figs. 3 and 4 to that shown by Fig. 6, the lever pin 15 sliding outwardly in slot 16 away from pivot 11 and lever 9 moving 110 downward in slot 21.

Referring now to the construction shown 115 in Figs. 7 and 8, bracket 5 and its several parts are substantially like those shown in Figs. 3 to 6. The box 26, however, is of a modified construction and unlike Fig. 3 there 120 is no short connecting lever in the box. On the other hand, the box is provided with a pivot boss 27 to engage the slot 16 of lever 9, said lever being constructed substantially 115 as in Figs. 3 to 6, and being mounted in like manner. The lever 8 is also similar to the corresponding lever above described and is mounted in the same manner. The cover 28 is modified somewhat in construction to cor- 125 respond with the different shape of the box and is provided with a stop 29 of modified form to secure the inner end of lever 8 in place.

In this instance the power delivered 125 through the hand lever 9 is transmitted by the box directly to the inner arm of lever 9. The box here operates substantially as a lever of the first order, though it may be regarded in a certain sense as in the nature 130

of a link connecting the slot end of lever 9 to the bearing point of lever 8 which enters at 26' and rests on the box shoulder 30. The effective part of the box, however, is more strictly of the nature of a lever to which the power is applied at 30 and delivered at 27, the fulcrum being at the bracket pivot 12.

In assembling this form of uncoupler, the lever 9 is first inserted through slot 31 into the box which is then mounted on the pivot 12 of bracket 5, care being taken that the bracket pivot 11 enters the slot 32 and the lever aperture 9'. The lever 8 is then inserted and finally the cover 28 is applied and locked in place substantially as in the first embodiment described. In this instance the pivot 27 slides outwardly in slot 16 when lever 8 tilts the box counter-clockwise.

Referring next to the embodiment shown in Figs. 9 and 10, the bracket 5 is the same as described in the first two forms. The box 35, however, is different in several ways, both in the exterior appearance and in the mechanical construction. In order to enhance the appearance, the box is made substantially round and disk-like so that when the uncoupler mechanism is operated, the tilting of the box will not be conspicuous or noticeable. It is somewhat thicker on the right side so as to accommodate the necessary side swing of lever 36 in slot 35'. Furthermore, the inner tip 37 of the pin lifting lever 36 is solid and the upper left part of the box is provided with a downwardly facing shoulder 38 against which the upper edge of the lever tip 36 bears for the transmission of power in effectively operating the uncoupler. The cover 39 is also formed round and substantially flat to correspond with the shape of the box. It is modified somewhat respecting the shoulder means for locking the hand lever 40 in place. In this instance a rib 41 stands out on the back side of the cover and is formed so as to provide a shoulder 42 underlying the inner part 43 of the hand lever, thereby preventing displacement of the latter downwardly when the cover is in place. A cotter 25 serves to lock the cover 39 in place substantially as above described. In mechanical principles this form of uncoupler is similar to that of Fig. 8. But here the shoulder 42 is formed differently and more substantially.

A still further and more distinct modification of the uncoupler is shown in Figs. 11 and 12. Here the parts are all modified to accommodate a variation in the mode of operation and to correspond with one another. The bracket 50 is formed with a central pivot 51 to receive the inner part of the hand lever 52. Slightly above said pivot is a pin lever supporting pivot 53. Mounted on the lower pivot is also a short connecting lever 54 pivoted at one end to the inner end of said hand lever as at 55. The inner end

of the pin lifting lever 56 and the other end of the short connecting lever are connected at 57 and 58 by a link 59. In this construction we have a hand lever 52 of the first order, a short connecting lever 54 of the first order, and a pin lifting lever 56 of the first order, the two last mentioned levers being connected by said link 59.

In assembling this device the bracket 50 is first secured to the car and then the two main levers 52 and 56 are mounted on their respective pivots 51 and 53.

The connecting lever 54 is then applied and finally the link 59 is attached to the adjacent ends of the corresponding levers 54 and 56 as will be understood. To accommodate these connections, the lever 56 has apertures 61 and 62 corresponding with the pivots 53 and 57 respectively. Lever 52 is apertured at 63 and 64 to receive the pivots 51 and 55 respectively. The lever 54 has the pivots 55 and 58 formed on its back and front sides respectively. Link 59 is apertured at its lower end to receive pivot 58 and has pivot 57 formed to project backwardly on its upper end to enter hole 62 of lever 56. The several pivots are provided with cotter pins 66 to secure them in their respective link and lever apertures.

It may be noted that in each embodiment here shown the two main levers, namely the hand operating lever and the pin lifting lever are disposed in the same vertical plane, the latter lapping over the former at their inner ends. Moreover, in all but the last form described, the housing box functions as a leverage connecting means mechanically intermediate the two main levers.

Although several specific embodiments or modifications of this invention are herein set forth, it will be understood that no attempt has been made to show all practical and useful embodiments of the invention, and that some of the details of the construction shown may be altered or omitted without departing from the spirit of this invention as defined by the following claims.

I claim:

1. An uncoupling device including a power multiplying leverage mechanism comprising in combination a fixed bracket having two fulcrum pivots thereon, a box oscillatably mounted on one of said pivots, a hand lever fulcrumed on said one pivot in coactive relation to said box, a pin lifting lever fulcrumed medially on the other of said pivots and means including said box operatively connecting said levers.

2. An uncoupling device including a power multiplying leverage mechanism comprising in combination a fixed bracket having two fulcrum pivots thereon, a box oscillatably mounted on one of said pivots, a hand lever fulcrumed on said one pivot in coactive relation to said box, a pin lifting

lever fulcrumed medially on the other of said pivots, a cover for said box serving to hold the said members in operative relation and releasable locking means engaging said one pivot to hold said cover in place on said box.

3. An uncoupling device including a power multiplying leverage mechanism comprising in combination a fixed bracket having two fulcrum pivots thereon, a box oscillatably mounted on one of said pivots, a hand lever fulcrumed on said one pivot in coactive relation to said box, a pin lifting lever fulcrumed medially on the other of said pivots directly above said hand lever and means including said box operatively connecting said levers, said box being arranged and connected to function as a leverage member.

4. An uncoupling device including a power multiplying leverage mechanism comprising in combination a fixed bracket having two fulcrum pivots thereon, a box oscillatably mounted on one of said pivots, a hand lever fulcrumed on said one pivot in coactive relation to said box for tilting the same, a pin lifting lever fulcrumed medially on the other of said pivots, a medially apertured cover for said box serving to hold the said members in operative relation and releasable locking means engaging said one pivot to hold said cover in place on said

box, said one pivot being disposed to project through the cover aperture to accommodate said locking means.

5. An uncoupling device including a power multiplying leverage mechanism comprising in combination a fixed bracket having two fulcrum pivots thereon, a box oscillatably mounted on one of said pivots, a hand lever fulcrumed on said one pivot in coactive relation to said box, a pin lifting lever fulcrumed medially on the other of said pivots directly above said hand lever and means including said box operatively connecting said levers, said box being arranged and connected to function as a leverage member.

6. An uncoupling device including a power multiplying leverage mechanism comprising in combination a fixed bracket having two fulcrum pivots thereon, a member oscillatably mounted on one of said pivots, a hand lever oscillatable about said one pivot co-turnably with said member, a pin lifting lever fulcrumed medially on the other of said pivots and means including said member operatively connecting said levers.

Signed at Chicago this 28th day of October 1924.

WILLIAM WRIGHT.
